UNITED STATES PATENT OFFICE

HOWARD B. HASKINS AND BURTON S. FLORADAY, OF TOLEDO, OHIO, AND DORR MILLER, OF DETROIT, MICHIGAN, ASSIGNORS TO THE DURA COMPANY, OF TOLEDO, OHIO, A CORPORATION OF OHIO

WINDOW REGULATOR

Continuation of application Serial No. 221,820, filed September 24, 1927. This application filed September 24, 1928. Serial No. 307,991.

The invention relates to window regulators and more particularly refers to window regulators for raising and lowering the windows of a vehicle. The invention has for 5 some of its objects the construction of a quick action window regulator having a lifter element and a pinion for moving the lifter element through its complete arc upon approximately one turn of the pinion; the provision 10 of a crank or handle for actuating the pinion and an irreversible drive mechanism between the crank or handle and the pinion so constructed that the lifter element may be readily and easily moved through its complete arc 15 upon approximately one turn of the crank or handle and may be effectively locked in its various positions of adjustment; and the provision of a window regulator of the above mentioned construction which is of a size to 20 fit and be properly positioned in a standard construction of vehicle body. Other objects are to so construct the window regulator that its crank or handle may be used as a pull-to handle for a vehicle door without damaging 25 the window regulator; to so construct the window regulator, to so mount the window and to so connect the window regulator to the window that all possible frictional resistance to the movement of the parts of the window 30 regulator or the window is eliminated. With these as well as other objects in view, the invention resides in the novel features of construction and combinations and arrangements of parts as more fully hereinafter set 35 forth.

This application is a continuation of our co-pending application Serial Number 221,820, filed September 24, 1927, which has been abandoned.

40 In the drawings:—

Figure 1 is an interior side elevation, partly broken away, of a vehicle door;

Figure 2 is an enlarged interior side elevation of a part thereof;

45 Figure 3 is an enlarged exterior side elevation of the window regulator;

Figure 4 is a cross section on the line 4—4 of Figure 3;

50 Figure 5 is a cross section on the line 5—5 of Figure 4;

Figure 6 is a cross section on the line 6—6 of Figure 5;

Figures 7, 8 and 9 are cross sections respectively on the lines 7—7, 8—8 and 9—9 of Figure 1;

55 Figure 10 is an enlarged side elevation of a portion of an upper runway;

Figure 11 is a cross section on the line 11—11 of Figure 10.

While the window regulator embodying 60 our invention may be used to raise and lower any of the windows of a vehicle, it is shown in the present instance as applied to the door beside the driver's seat of a motor vehicle, where it is particularly desirable. This door 65 has the hinge and lock pillars 1 and 2, respectively, with the hinge pillar shown in advance of the lock pillar, the lock board 3, the opening 4 above the lock board and the chamber 5 below the opening and adapted to 70 receive the window 6 when lowered from a position closing the opening. In the present instance, the door is of standard construction and the window is a sashless glass.

7 is the window regulator having the 75 mounting plate 8, which is preferably stamped from sheet metal and is secured to and depends from the lock board 3 near the hinge pillar 1. 9 is the crank or handle of the window regulator, which through suitable drive mechanism operates the lifter element 10, which latter is operatively connected to the window 6 to raise and lower the same. The lifter element comprises the lifter arm 11 and the gear segment 12, both being preferably formed from sheet metal and the former being in the plane of and at one edge of the latter. This lifter arm is set into and welded to the gear segment as at 13. The gear segment is fixedly secured to the 80 pivot 14, which is journaled in the lower end portion of the mounting plate 8 below the lock board 3, the lifter element including the gear segment and lifter arm being adjacent the outer side of the mounting plate. 85 15 is a convolute counterbalancing spring adjacent the inner side of the mounting plate and below the lock board and having its inner end engaging in the diametrical slot 16 of the pivot 14 and its outer end 90 100

formed with a hook 17 engaging one of the transverse lugs 18 upon the mounting plate, the arrangement being such that as the window is lowered the spring is wound up. The lugs are in the nature of flanges symmetrically arranged on opposite sides of the longitudinal median line of and preferably integral with the mounting plate.

The driving connection between the crank or handle and the lifter element comprises the pinion 25 and the irreversible drive mechanism 19.

The pinion 25 meshes with the gear segment 19 and the ratio of the numbers of teeth of the pinion and gear segment is such that approximately one turn or revolution of the pinion moves the lifter element and more particularly the lifter arm through its complete operative arc to raise the window from its lowermost or fully open position to its uppermost or fully closed position or to lower the window from its uppermost or fully closed position to its lowermost or fully open position. As shown in the present instance, the gear segment has some teeth at its ends which do not intermesh with the teeth of the pinion, while the lifter arm is being moved through its complete operative arc, these extra teeth being present to take care of any variations in location of the window regulator in the door or relative to the travel of the window.

The irreversible drive mechanism is proportional to the ratio of the numbers of teeth of the pinion and gear segment to effectively lock the lifter element and more particularly the lifter arm in its various positions of adjustment. The driving member of this irreversible drive mechanism comprises the shaft 20 and the cupped sheet metal member 21 fixedly secured to the shaft 20 and having diametrically opposite transverse fingers 22. The driven member of the irreversible drive mechanism comprises the cupped sheet metal member 23, having diametrically opposite fingers 24, and the bushing 26, which fixedly secures the pinion 25 to the cupped member 23. The fingers 24 engage between the fingers 22 and both sets of fingers are surrounded by a coil spring 27, which has a strength proportional to the ratio of the numbers of teeth of the pinion and gear segment and is provided with in-turned ends located between one of the fingers 22 and on opposite sides thereof and the fingers 24. The housing for the irreversible drive mechanism comprises the sheet metal cup 28 and the cupped sheet metal plate 29, the cupped driving and driven members 21 and 23, respectively, and the coil spring 27 being housed within the cup 28 and the spring being adapted to normally frictionally engage the inner periphery of the cup. This cup has at its outer end the cylindrical flange 30 in which the portion of the shaft

20 adjacent the crank is journaled. The cupped plate 29 has fixedly secured thereto, and thereby supports, the pin 31 which extends axially through the bushing 26 and into the shaft 20 and terminates substantially opposite the cylindrical flange 30. This pin thus forms an additional bearing for the shaft 20 and also forms a bearing for the driven member of the irreversible drive mechanism. The lower peripheral portion of the cupped plate is outwardly offset at 29' to provide for passage of the gear segment at the inner side of the web of the cupped plate.

With this arrangement it will be seen that the irreversible drive mechanism may be directly actuated by the crank or handle and that the driven member of the irreversible drive mechanism is rotatable with the crank or handle after the slight lost motion of the crank or handle necessary to release the coil spring from locking engagement has taken place. As a result, the lifter element and more particularly the lifter arm may be moved through its complete operative arc with approximately one turn or revolution of the crank or handle, thereby making the window regulator a quick action or high gear window regulator. The strength of the irreversible drive mechanism being proportional to the ratio of the teeth of the pinion and gear segment, this mechanism serves to effectively lock the lifter element and more particularly the lifter arm in its various positions of adjustment.

The crank or handle 9 is adapted to be fixedly secured to the inner end of the shaft 20 and has a length proportional to the ratio of the numbers of teeth of the pinion and gear segment so that the window regulator may be readily and easily operated thereby. This crank or handle is, however, relatively short as compared to the crank or handle of any quick action window regulator heretofore developed and the mounting plate 8 is so positioned that when the knob of the crank is in its furthermost advanced position relative to the door it terminates short of the edge of the window at the hinge edge of the door.

The mounting plate has a width also proportional to the ratio of the numbers of teeth of the pinion and gear segment to withstand the driving force required to move the lifter element through its arc. This mounting plate is furthermore provided with the spaced longitudinally extending relatively shallow reinforcing ribs 8² to assist in holding the lower portion of the mounting plate from flexing laterally upon application of driving force to move the lifter element through its arc.

While the window regulator as above described is constructed to effect the movement of the lifter element through its complete operative arc upon approximately one turn or revolution of the crank or handle or the

pinion, the parts are so designed that when assembled to form the window regulator, the size and particularly the thickness of the window regulator is such that it may be properly positioned in the door and connected to the window for ready operation without changing the door construction.

To provide for using the crank or handle 9 as a pull-to handle for the door without damaging the window regulator and more particularly the irreversible drive mechanism, the cup 28 has at its outer end the annular flange 32 which serves as an anchoring portion and is located at the outer side of the mounting plate so that any pull upon the crank or handle is directly resisted by the mounting plate. The peripheral portion of the cupped plate 29 rests against the annular flange 32 and both are rigidly secured in place as by means of suitable rivets, which extend through the mounting plate.

The lower peripheral portion of the cupped plate 29 preferably has the inwardly extending bosses 29² and the mounting plate 8 preferably has the outwardly extending bosses 8' to engage and guide the gear segment.

It is highly important to eliminate all possible frictional resistance to the movement of the parts of the window regulator or the window. This is accomplished by eliminating the frictional resistance between the convolutions of the counterbalancing spring, by reducing to the minimum the frictional resistance in the connection between the lifter arm and the window, and by reducing to the minimum the frictional resistance offered to the movement of the window itself at the same time maintaining a good seal, avoiding rattling, and providing for large variations in the thickness and width of the window as well as distances between the hinge and lock pillars of the door.

To eliminate friction between the convolutions of the counterbalancing spring 15, there are the transverse projections 33 upon the lower end portion of the mounting plate 8 and preferably integral therewith, these projections being in the nature of transverse flanges for reinforcing the mounting plate. There are two of these projections arranged symmetrically on opposite sides of the longitudinal median line of the mounting plate, each having a concave portion 34 which is substantially concentric with the axis of the pivot 14. These concave portions are alternatively engageable with the outer convolution of the counterbalancing spring to thereby hold the same more truly circular, which operates to hold the remaining convolutions more truly circular and out of contact with each other. Specifically, the concave portion in engagement with the counterbalancing spring is on the side of the longitudinal median line of the mounting plate opposite to the transverse lug 18 engaged by the hook 17 of the spring.

By reason of this arrangement the one mounting plate may be used either with a right or left hand window regulator.

To eliminate all possible friction in the connection between the lifter arm 11 and the window 6, the glass forming the window has fixedly secured to its lower edge the sheet metal channel 6' to which is fixedly secured the retainer 35 having a depending flange which is vertically bowed outwardly and is formed with vertically spaced longitudinally extending return bent portions 37 between its upper and lower edges forming a longitudinally extending slot. 38 is a pin fixedly secured to the outer end of the lifter arm and extending outwardly through the slot and having at its outer end the head 39 forming a shouldered portion for engaging the outer sides of the return bent portions. The shoulder of the head is held in engagement with these return bent portions as by means of the coil spring 40 encircling the pin and abutting the lifter arm and the concave washer 41, which latter also encircles the pin and abuts the inner side of the depending flange. 90 By reason of the return bent portions, smooth bearing surfaces are obtained so that they offer the minimum frictional resistance to movement of the pin along the slot. The coil spring holds the parts from rattling. 95

To eliminate all possible frictional resistance to the movement of the window, at the same time maintaining a good seal and taking care of large variations in the thickness and width of the glass forming the window, as well as distances between the pillars, the means for guiding the glass includes the pairs of upper and lower runways 42 and 43 at the opposite edges of the glass, the upper runways extending downwardly to a position to overlap the glass when in its lowermost position and the lower runways abutting the upper runways. Each of the lower runways has a sheet metal channel-shaped strip 44 and a lining 45 of fibrous material, such as felt, which is permanently secured to the metal strip as by being cemented thereto. Rolls 46 of relatively large diameter run in these lower runways, these rolls being mounted upon the brackets 47 which are fixedly secured to the channel 6' near its ends. 110

The upper runways are highly flexible to take care of the variations previously noted and also to take care of misalignment of the lower with the upper runways, which latter might occur during commercial manufacture. Each of these upper runways has the sheet metal retainer strip 48 which is suitably secured to the hinge and lock pillars and which has at its opposite edges the transverse flanges 49, from which are severed the tongues 50, which are bent inwardly to embrace the resilient strip 51, preferably formed of rubber, and to secure this strip to the retainer strip. 52 are sheet metal side strips, 130

which have their inner portions formed with the transverse foot flanges 53 extending under the resilient strip 51 and clamped thereby against the base of the retainer strip 48. 5 The inner portions of these side strips are cut away to form sections between which the tongues 50 pass and the side edges of the sections are spaced a sufficient distance from the side edges of the tongues to provide sufficient lengths of the resilient strip therebetween to allow the side strips to separate through a relatively wide range. The side strips have the continuous outer portions 54 which are located outwardly beyond the 10 transverse flanges 49 and converge toward each other and terminate in beaded outer edges 55. 56 is a fabric which is of a general channel shape, but has its sides converging from its base to its outer edges. This 15 fabric is preferably formed of felt and its base is permanently secured to the resilient strip 51 as by stitching and the outer edges of its sides are permanently secured to the beaded edges 55 as by being clamped by these 20 beaded edges against the outer sides of the side strips.

With this arrangement rounded surfaces 30 of the fabric are provided for single line contact with the opposite sides of the glass to oppose the least possible resistance to its movement. Also with this construction the upper runways take care of large variations in thickness of the glass since the side strips are movable through a relatively wide range. 35 Furthermore, by reason of the arrangement of the side strips and resilient strips in which the outer portions of the side strips are yieldably held against the glass by a resilient strip, and also by reason of the relatively 40 large rolls engaging in the lower runways, the glass guideway takes care of large variations in the width of the glass and in the distances between the pillars and at the same time maintains an effective seal.

45 From the above description it will be readily seen that we have provided for using a quick action or high gear window regulator, which is constructed to fit and be properly positioned in a standard construction of vehicle body and which, moreover, may be operated with substantially the same effort as required for the ordinary slow action or low gear window regulators. It will also be seen that we have provided a simple construction 50 of window regulator which permits using the crank or handle as a pull-to handle for a door without liability of damaging the window regulator. It will furthermore be seen that the arrangement is such that frictional resistance throughout is either removed or reduced to the minimum.

What we claim as our invention is:

1. In a window regulator, the combination 55 of a mounting plate, a lifter element upon said mounting plate, a convolute coun-

terbalancing spring having one end secured to the lifter element and the other end secured to the mounting plate, and means engageable with the spring for holding the convolutions thereof from frictional engagement with each other to thereby decrease the frictional resistance offered to movement of the lifter element. 70

2. In a window regulator, the combination 75 of a mounting plate, a lifter element upon the mounting plate, a convolute counterbalancing spring having one end secured to the lifter element and the other end secured to the mounting plate, and a projection upon the mounting plate engaging the outer convolution of the spring to hold its convolutions from frictional engagement with each other. 80

3. In a window regulator, the combination 85 of a window regulator for use with right or left hand window regulators, a lifter element journaled in the mounting plate, a convolute counterbalancing spring having one end secured to the lifter element and the other end secured to the mounting plate, and 90 transverse projections upon the mounting plate alternatively engageable with the spring to hold its convolutions from frictional engagement with each other.

4. An easily operated quick action window 95 regulator comprising a lifter arm, a gear segment connected to the lifter arm, a pinion meshing with the gear segment, a crank, and means locking the lifter arm in its various 100 positions of adjustment, the parts being so related that the lifter arm may be easily moved through its complete operative arc upon approximately one turn of the pinion and effectively locked in its various positions of adjustment. 105

5. An easily operated quick action window 110 regulator comprising a lifter arm, a gear segment connected to the lifter arm, a pinion meshing with the gear segment, a crank, and means between the pinion and 115 crank for driving the former from the latter through substantially the same angle, the parts being so related that the lifter arm may be easily moved through its complete operative arc upon approximately one turn of the crank.

6. An easily operated quick action window 120 regulator comprising a mounting plate, a lifter element pivotally mounted upon the mounting plate and comprising a lifter arm and a gear segment fixed to each other, a pinion carried by the mounting plate and meshing with the gear segment, a crank, and irreversible drive mechanism carried by the mounting plate for driving the pinion from the crank through substantially the same angle, the lifter element, pinion and crank being 125 so related that the lifter element may be easily moved through its complete operative arc upon approximately one turn of the crank 130

and the mounting plate having a width such that it will withstand the driving force required to move the lifter element through its arc.

7. An easily operated quick action regulator for a window comprising a lifter arm, a gear segment connected thereto, a pinion meshing with the gear segment, a crank, means for connecting the lifter arm to the window so that the lifter arm is freely movable relative to the window, means for guiding the window so that the window is freely movable relative to the guiding means, the parts being so related that the lifter arm 10 may be easily moved through its complete operative arc upon approximately one turn of the crank.

In testimony whereof we affix our signatures.
